UNITED STATES PATENT OFFICE

127,833

DESIGN FOR AN ADJUSTABLE ILLUMINATING DEVICE

Edison Avery Price, New York, N. Y.

Application June 7, 1940, Serial No. 92,881

Term of patent 7 years

To all whom it may concern:

Be it known that I, Edison Avery Price, a citizen of the United States of America, residing at New York city, county of New York, Borough of Manhattan, and State of New York, have invented a new, original, and ornamental Design for an Adjustable Illuminating Device, of which the following is a specification, reference being had to the accompanying drawing, forming a part thereof.

Figure 1 is a perspective view of the adjustable illuminating device showing my new design.

Figure 2 is a bottom view of the device shown in Figure 1 with the lens in its lowest position.

Figure 3 is a side elevational view of Figure 1.

Figure 4 is a front elevational view of Figure 1.

The broken lines appearing at the support ends in Figures 1, 3 and 4, are employed to indicate indeterminate length.

I claim:

The ornamental design for an adjustable illuminating device, as shown and described.

EDISON AVERY PRICE.
